UNITED STATES PATENT OFFICE.

WILLIAM M. PERKINS, OF NORTH MANCHESTER, INDIANA.

AUTOMATIC DANGER-SIGNAL FOR RAILWAYS.

1,176,923.

Specification of Letters Patent. Patented Mar. 28, 1916.

Application filed May 6, 1915. Serial No. 26,196.

To all whom it may concern:

Be it known that I, WILLIAM M. PERKINS, a citizen of the United States, residing at North Manchester, in the county of Wabash 5 and State of Indiana, have invented certain new and useful Improvements in Automatic Danger-Signals for Railways; and I do hereby declare the following to be a full, clear, and exact description of the invention, 10 such as will enable others skilled in the art to which it appertains to make and use the same.

This invention is in the nature of an automatic danger signal for railways.

15 The object of the invention is to provide a simple, inexpensive, durable and thoroughly practicable mechanism for operating danger signals on railways.

A further object is to provide, in connection with such operative mechanism for danger signals, a lighting system whereby when the danger sign is exposed, a warning light will be also operated.

With these objects in view the invention 25 consists in the improved construction, arrangement and combination of the parts of a device of the character mentioned, which will be hereinafter fully described and afterward specifically claimed.

30 In order that the construction and operation thereof may be readily comprehended, an approved embodiment of the invention is illustrated in the accompanying drawings and will be now specifically described in connection with said drawings, in which,

Figure 1, represents in elevation, partly in section, an approved mechanism for carrying out my invention, the connecting parts of the mechanism being broken out to 40 shorten the figure. Fig. 2, a top plan view of a portion of the system including the road bed mechanism for operating the signal levers. Fig. 3, an elevation of the primary signal operating mechanism, Fig. 4, a view 45 of the opposite side of the housing from that shown in Fig. 1, and, Fig. 5 is an end elevation of a housing used in connection with my improved signaling mechanism with parts attached thereto.

50 Like characters of reference mark the same parts in all of the figures of the drawings.

In this specification, to the right, on Figs. 1, 2 and 3, will be considered as forward and 55 to the left as rearward, in referring to the

movement of a train over the track, such directions being reversed in Fig. 4.

Referring specifically to the drawings, 5 indicates the ordinary railway rails and 6 a cross bar or weight in substantially the position of a cross tie, connecting the two rails at the middle point of my mechanism.

7, 7, indicate levers or false rails pivoted as at 8 to the side of one of the rails and extending toward each other to a point 8^a 65 just above the cross bar 6, sufficient space being left at this point to permit the inner ends 9 of the false rails 7 to be pressed down upon the cross bar 6.

At 10 is erected alongside the railway, a 70 standard in which is journaled on a pivotal pin 11 an elbow lever which comprises arms 12 and 13. The arm 12 is attached by a rod or link 14 to the outer end of cross bar 6 at the point 8^a, Fig. 2, while the arm 13 is connected to a rod or cable 15 which passes over a pulley 18 mounted in a frame or housing 19, and is connected at its lower end to a weight 20 in the housing. A similar cable 21 connected to the weight 20 passes upward 75 over a pulley 22 and outward, its outer end being connected at 23 with a danger signal or gate bar 24 pivoted to the housing.

At 25, a latch 26 is pivoted to the housing which, at its inner end, as at 27, is connected 80 by a link 28 to an elbow lever 50 pivoted at 51 to the reverse side of the housing, said elbow lever being connected at its opposite end, as at 52, to a cable 15^a which extends 85 rearwardly, beyond the standard 10, to the primary operating mechanism of my system, as in Fig. 3, consisting of an elbow lever having an arm 13^a, to which the cable 15^a is secured and an arm 12^a pivoted at 11^a to a standard 10^a and an elbow weighted lever 7^a, 90 pivoted along side of the rails 5 in a position to be passed over by a forwardly moving train before reaching the middle mechanism before described. The arm 12^a is connected by a link 14^a to a cross bar 6^a which is 95 pressed down when the elbow weighted lever is tilted by a passing train to depress said cross bar. A pin 29 projects from the side of the housing in the path of the latch 26 which serves to limit its downward movement to a proper operative position.

At 30, a latch 31 is pivotally connected to the housing which serves, when the danger signal or gate bar 24 is lowered and in operative position, as shown in dotted lines in 110

Fig. 1, to hold said signal in such operative position. The inner end of the latch 31 is connected at 33 by means of a link 34 with a lever 35 pivoted at 32 to the housing, having a weighted end 36 and carrying at its outer end, as at 37, suitable links and rods 38 which connect it at 39 with the meeting ends of the two levers or false rails 40, 40. The rails 40, 40 are of a construction similar to the levers 7, 7, and pivoted in a like manner at 41, 41 to the sides of the rail.

The operation of the mechanism thus far described may be described as follows: With the parts in the position illustrated in Fig. 1, the danger signal or gate bar 24 is raised indicating that the crossing at which said signal is located is safe to be used by passing animals and vehicles. A train approaching, as from the left in Fig. 1, the wheels running upon the rails 5 will tilt the weighted elbow lever 7^a, 7^a, and depress the cross bar 6^a and thus draw downward the connecting link 14^a, whereby the elbow lever will be operated on its pivot swinging the arm 13^a to the left, drawing on the cable 15^a swinging the elbow lever on its pivot, drawing down on link 28 and raising the latch 26 off the signal or gate bar 24. In continuing its passage to the right over the rails 5 the train will ride over false rails 7, 7, depressing cross bar 6, drawing down on arm 12 of the elbow lever, swinging the arm 13 thereof to the left and carrying with it the connecting rod or cable 15, and at the same time raising the weight 20 allowing the cable 21 to slack which will permit the danger signal or gate bar 24 to drop to the danger position shown in dotted lines in Fig. 1. When the danger signal reaches its operative position as shown in dotted lines in Fig. 1, it will be engaged by the latch 31 which is formed with an upward and outwardly extending end which engages the outer edge of the signal 24 and held down normally in that position by the weight 36 on the lever 35. The engine or train continuing to move toward the right will now ride up on the levers 40 or false rails, depress them at their point of junction 39, draw down the outer end of the lever 35, pull down on link or rod 34, lower the inner end of the latch 31 and release said latch from the danger signal or gate bar 24. The pull of the weight 20 upon the cable 15 will operate the elbow lever 12, 13, to the right, raise the levers 7, 7, to operative position and at the same time the weight 20 pulling on the cable 21 will draw the danger signal 24 into position, shown in full lines in Fig. 1, where it will be engaged by the latch 26 and held in that position until another engine or train operates the levers 7^a, 7^a, and 7, 7. A weighted elbow lever similar to the lever 7^a, may be substituted for the false rails 40, 40, if desired. In order to combine an illuminating signal with the

danger signal thus described, I provide a battery 42, from which extends a wire 43 upward and along the danger signal to an electric lamp 44 from which said wire is continued at 45 to a contact plate 46 on the signal. This circuit is completed by another wire 47 extending from the battery up a post 48 to a contact plate 49 on said post. The two plates 46 and 49 are in contact when the danger signal is down, or in operative position, as shown in dotted lines in Fig. 1, and the circuit is completed so that the lamp 44 will be lighted whenever the danger signal is down. When the danger signal is raised, however, to inoperative position, the plate 46 is moved off the plate 49, this breaking the circuit and putting out the light.

The construction, practicability, economy and durability of the mechanism comprising my invention will be obvious from the foregoing description, and it will be further obvious that changes and variations may be made in the specific construction and arrangement of the parts without departing from the spirit and the scope of the invention.

Having thus fully described my invention what I claim as new and desire to secure by Letters Patent is:—

1. In a railway signal, the combination of a weight, two cables extending upward from said weight, a signal board connected to one of said cables, an elbow lever actuated by the passage of a train and connected to the other cable, a latch for holding the signal board in raised or inoperative position, means for releasing the latch, and a weighted latch normally holding the signal board in depressed or operative position.

2. In a railway signal, the combination of a weight, two cables extending upward from said weight, a pivoted signal board connected to one of said cables, an elbow lever actuated by the passage of a train and connected to the other cable, a latch for holding the signal board in raised or inoperative position, means for releasing the latch, a weighted latch normally holding the signal board in depressed or operative position, a pair of depressible levers pivoted to the side of the railway rail, an intermediate pivoted lever connected at its outer end to the meeting ends of the said pair of levers, and a link connecting the intermediate lever to the last named latch.

3. An automatic signal system comprising a housing, a signal board pivoted thereto, a weight in the housing, a connection from the signal board to the weight, a pair of false rails pivoted to the track, a weighted cross bar under the false rails, a standard, an elbow lever pivoted thereon, a link connecting one arm of the elbow lever to the cross bar, and a cable connecting the other

arm of the elbow lever to the weight in the housing.

4. An automatic signal system comprising a housing, a signal board pivoted thereto, a weight in the housing, a connection from the signal board, to the weight, a pair of false rails pivoted to the track, a weighted cross bar under the false rails, a standard, an elbow lever pivoted thereon, a link connecting one arm of the elbow lever to the cross bar, a cable connecting the other arm of the elbow lever to the weight in the housing, a latch pivoted in the housing, adapted to hold the signal board down, a weighted lever pivoted in the housing, a link connecting the pivoted lever with the latch, a pair of false rails at the housing, a cross bar under the false rails, and connections between the cross bar and the weighted lever.
- 10 5. An automatic signal system comprising a housing, a signal board pivoted thereto, a weight in the housing, a connection from the signal board to the weight, a pair of false rails pivoted to the track, a weighted cross bar under the false rails, a stand-
- ard, an elbow lever pivoted thereon, a link connecting one arm of the elbow lever to the cross bar, a cable connecting the other arm of the elbow lever to the weight in the housing, a weighted elbow lever pivoted to the 30 rail in advance of the false rails, a cross bar under said weighted elbow lever, a standard, an elbow lever pivoted on the standard, connections between one arm of the elbow lever and the cross bar, a latch in the housing to hold the signal board up, an elbow lever pivoted in the housing, connections between one arm of the elbow lever and the latch, and connections between the other arms of the two elbow levers whereby to release the latch when the weighted elbow lever is tilted by a train.
